UNITED STATES PATENT OFFICE.

ERIC R. LUNDIUS, OF BROOKLYN, NEW YORK, ASSIGNOR TO WESTERN ELECTRIC COMPANY, INCORPORATED, OF NEW YORK, N. Y., A CORPORATION OF NEW YORK.

TESTING SYSTEM.

1,293,825.

Specification of Letters Patent. Patented Feb. 11, 1919.

Application filed April 6, 1918. Serial No. 227,038.

To all whom it may concern:

Be it known that I, ERIC R. LUNDIUS, a citizen of the United States, residing at Brooklyn, in the county of Kings, State of New York, have invented certain new and useful Improvements in Testing Systems, of which the following is a full, clear, concise, and exact description.

This invention relates to telephone systems and more particularly to testing means for such systems.

Heretofore, in providing testing means for separately testing the portion of the telephone line from the subscriber's station to the main frame, and the portion extending from the main frame to the switchboard, it has been customary to provide switching devices for interrupting the continuity of the telephone line at the main frame or test panel and circuits for looping the telephone line through a test desk. When the test desk is located at a point distant from the central office at which the telephone line terminates, the resistance of the loop between the central office and the test desk becomes such as to cause considerable transmission loss whenever the telephone line is connected up for testing purposes. Furthermore, the cost of the looping conductors between the central office and the test desk is considerable. It is, therefore, the object of the present invention to provide testing means in connection with test desks located at a point distant from the central office at which terminates the line to be tested, so that practically no transmission loss results from connecting a telephone line up for testing purposes and in which the number of conductors required between the central office and the test desk is reduced to a minimum.

In accordance with the features of this invention, there is provided a test line or trunk extending from the test desk to the central office where it is double-ended to form a looping circuit when connected with a telephone line which is to be tested. This test line or trunk comprises three conductors, two of which are employed for testing purposes and a third for controlling switching apparatus at the central office by means of which a testing operator may at will test either section of the telephone line.

This invention will be more fully understood from the following description considered in connection with the accompany-

ing drawing illustrating one embodiment thereof.

As shown in the drawing, a telephone line A incoming from a subscriber's station to a central office switchboard and there terminating in the usual answering jack before reaching the switchboard, passes through switches in the form of jacks 3 and 4, preferably located at either a test panel or a main distributing frame. A test line B, terminating at the central office in a pair of plugs 5 and 6 for connection with the telephone line A, extends to a test desk located in another office where it terminates in two jacks 7 and 8. When the test line B is connected with the telephone line A, the telephone line is then looped through contacts of switching apparatus in the test line located at the central office and controlled from the test desk. A cord circuit C provided at the test desk may coöperate with either jack of the test line B.

When connected with one jack, the switching apparatus functions to interrupt the continuity of the connected telephone line and to extend one section thereof to the test desk, while if connected with the other jack the continuity of the telephone line is interrupted and the other section thereof is extended to the test desk. The apparatus shown to the right of the dotted line 2—2 is located at the test desk, while that shown to the left thereof is located at the central office.

The testing operator desiring to test the telephone line A communicates over a separate circuit (not shown) with an attendant at the central office and requests that the test line B be connected with the telephone line A. When the plugs 5 and 6 of the test line B are inserted into the jacks 3 and 4 of the telephone line A, the continuity of the line is broken at the normally closed contacts of the jacks, but is immediately re-established through the normally closed contacts of two relays 9 and 10, associated with the central office end of the test line B. If, while the test line B is connected with the telephone line A, the subscriber thereof should initiate a call in the usual manner, the removal of the receiver from the switchhook causes the operation of the line relay 11 over a circuit from battery through the right-hand winding of relay 11, right-hand contact of cutoff relay 12, tip contacts of the jack 4 and plug 6, right-hand normal contacts of relays 10 and 9, tip con-

tacts of the plug 5 and the jack 3, out over the other side of the line, through the station apparatus and back over the other side of the line, sleeve contacts of the jack 3 and the plug 5, left-hand normal contacts of the relays 9 and 10, sleeve contacts of the plug 6 and the jack 4, left-hand contact of cutoff relay 12 and left-hand winding of relay 11 to ground. Line relay 11, in operating, 10 lights line lamp 11 in the usual manner and the call may be answered as usual by the switchboard operator. It will be noted, therefore, that the mere connection of the test line B with the telephone line A does not interfere with the usual working of such telephone line, and that practically no increase in length of line results from such connection.

The testing operator may now proceed 20 with the testing of the telephone line A. This is usually accomplished by first actuating key 14 and inserting plug 15 of the cord circuit C into one of the jacks, for example, jack 7, and then actuating the listening key 25 16. The purpose of plugging in when the key 14 is actuated is to prevent the interruption of the telephone line should it happen that a conversation is being carried on at that time. Finding that no conversation is 30 being carried on over the telephone line A, the testing operator may restore the key 14 to normal position, whereupon the relay 20, operating over a circuit from battery through the contact of the key 14, resistance 35 21, sleeve contacts of the plug 15 and the jack 7, resistance 22, windings of relays 10 and 20, to ground. Relay 10 is marginal and does not operate when resistance 22 is included in circuit therewith. Relay 20, in operating causes the operation of relay 9, which opens its contacts, interrupting the continuity of the telephone line A, and disconnecting from the trunk circuit B that portion of the telephone line which extends 40 45 from the jack 3 to the subscriber's station, and leaving connected with the test desk, that portion of the telephone line from the jack 4 to the switch-board.

If the testing operator desires to test the 50 portion of the telephone line A extending from the jack 3 to the subscriber's station, the plug 15 is inserted into the jack 8, and key 14 is restored to normal position. Relays 10 and 20 are thereupon operated. Relay 20, in operating, causes the operation of relay 9 as above described. Relay 10, in operating, serves to keep the continuity of the telephone line A and to leave connected to the test desk, through the trunk circuit B, 55 60 that portion of the telephone line extending from the jack 3 to the subscriber's line.

If the testing operator upon making connection with either of the jacks 7 and 8 should find that the telephone line A is not 65 in use, the testing of either portion thereof

may be carried on without interfering with the use of the line by the subscriber. This may be accomplished by the momentary actuation of key 22', whereupon relay 23 is energized over a circuit from battery, through the winding of relay 23 and contact of key 22' to ground. Immediately upon being energized, relay 23 establishes a locking circuit for itself through its middle contact and the contact of relay 20 to ground. Relay 23, in closing its right and left-hand contacts, connects condensers 24 and 25 in multiple with the normally closed contacts of relays 9 and 10. The key 14 is restored to normal position simultaneously with the operation of the key 22', so that the relay 20 is operated simultaneously with the operation of relay 23. The energization of either relay 9 or 10 interrupts the continuity of the telephone line A with respect to direct current before leaving them, but not to telephonic currents, for the two portions of the line are joined through the contacts of relay 23 and the condensers 24 and 25. Upon disconnection of the plug 15 from either jack, all apparatus associated with the testing line or trunk line B is restored to normal position, and the disconnection of the plugs 5 and 6 from the jacks 3 and 4 restores the continuity of the line through the contacts of the jacks.

What is claimed is:

1. In a telephone system, a telephone line extending between two separated points, a trunk circuit connected with the telephone line at a point intermediate its ends and extending to a switchboard, an extension circuit at the switchboard, a switching device thereat having two operative positions and when in either connecting the extension circuit with the trunk circuit, switching means responsive to the connection of the extension circuit with the trunk circuit when the switching device is in one operative position to open the telephone line and disconnect one end thereof from the trunk circuit, and means including the switching means responsive to the connection of the extension circuit with the trunk circuit when the switching device is in its other operative position to open the telephone line and disconnect the other end thereof from the trunk circuit.

2. In a telephone system, a telephone line extending between two separated points, a trunk circuit connected with the telephone line at a point intermediate its ends and extending to and terminating at a switchboard in two jacks, an extension circuit at the switchboard, switching means responsive to the connection of the extension circuit with one of the jacks to open the telephone line and to disconnect one end thereof from the trunk circuit, and means including said switching means responsive to the connection of the extension circuit with the other

jack to open the telephone line and disconnect the other end thereof from the trunk circuit.

3. In a telephone system, a telephone line extending between two separated points, a trunk circuit connected with the telephone line at a point intermediate its ends and extending to and terminating at a switchboard in two jacks, a plug-ended extension circuit at the switchboard, a switching relay responsive to the connection of the plug of the extension circuit with one jack of the trunk circuit to open the telephone line and disconnect one end thereof from the 15 trunk circuit, a second switching relay responsive to the connection of the plug of the extension circuit with the other jack of the trunk circuit to open the telephone line and disconnect the other end thereof from the 20 trunk circuit.

4. In a telephone system, a telephone line extending between two separated points, a trunk circuit connected with the telephone line at a point intermediate its ends and 25 extending to and terminating at a switchboard in two jacks, a plug-ended extension circuit at the switchboard, an operating circuit established upon the connection of the plug of the extension circuit with either 30 jack of the trunk circuit, a relay in the operating circuit responsive when the plug is connected with one jack to cause the opening of the telephone line and the disconnection of one end thereof from the trunk circuit, 35 and a second relay in the operating circuit responsive to the connection of the plug with the other jack to open the telephone line and to disconnect the other end thereof from the trunk circuit.

5. In a telephone system, a telephone line extending between two separated points, a trunk circuit connected with a telephone line at a point intermediate its ends and extending to and terminating at a switchboard in 45 two jacks, a plug-ended extension circuit at the switchboard, an operating circuit established upon the connection of the plug with either jack, two relays in the operating circuit responsive to the connection of the 50 plug with one jack to open the telephone line and disconnect one end thereof from the trunk circuit, and a resistance included in the operating circuit when the plug is connected with the other jack, whereby but one 55 relay is responsive to cause the opening of the telephone and the disconnection of the other end thereof from the trunk circuit.

6. In a telephone system, a telephone line extending between two separated points, a 60 trunk circuit connected with the telephone line at a point intermediate its ends and extending to and terminating at a switchboard in two jacks, a plug-ended extension cir-

cuit at the switchboard, and a relay responsive to the connection of the plug-ended extension circuit with the trunk circuit through either of the jacks, and means operating upon the response of the relay to open the telephone line and to disconnect one end thereof from the trunk circuit. 65 70

7. In a telephone system, a telephone line extending between two separated points, a trunk circuit connected with the telephone line at a point intermediate its ends and extending to and terminating at a switchboard in two jacks, a plug-ended extension circuit at the switchboard, a relay responsive to the connection of the plug-ended extension circuit with one of the jacks of the trunk circuit, and means operating upon 75 the response of the relay to open the telephone line and to disconnect one end thereof from the trunk circuit. 80

8. A telephone system comprising a telephone line extended between two separated points, a trunk circuit connected with the telephone line at a point intermediate its ends and extending to and terminating at a switchboard in two jacks, a plug-ended extension circuit at the switchboard, an operating circuit established upon the connection of the plug with either jack, a relay in the operating circuit responsive to the connection of the plug with one jack to cause 85 the opening of the telephone line and the disconnection of one end thereof from the trunk circuit, and a marginal relay responsive to the connection of the plug with the other jack to cause the opening of the telephone line and the disconnection of the 90 other end thereof from the trunk circuit. 95 100

9. In a telephone system, a telephone line, a trunk circuit connected with the line at a point intermediate its ends and extending to a switchboard, operator-controlled switching means at the switchboard, an electromagnetic switching mechanism in the trunk circuit responsive to the actuation of the operator-controlled switching means for interrupting the continuity of the telephone line and disconnecting one end thereof from the 105 trunk circuit. 110

10. In a telephone system, a telephone line, a trunk circuit connected with the telephone line at a point intermediate its ends and extending to a switchboard, an operator-controlled switch at the switchboard, and a relay in the trunk circuit responsive to the actuation of the switch to interrupt the continuity of the telephone line and to disconnect one end thereof from the trunk circuit. 115 120

In witness whereof, I hereunto subscribe my name this 27th day of March A. D., 1918.

ERIC R. LUNDIUS.
